TAKE-APART TOY GUN OR THE LIKE

Roy F. Constan, Staten Island, N.Y., assignor to De Luxe
Reading Corp., Elizabeth, N.J., a corporation of New Jersey

Filed June 19, 1964, Ser. No. 80,475

Term of patent 7 years

(Cl. D34—15)

The broken line showing of a missile is for illustrative purposes only.

I claim:

The ornamental design for a take-apart toy gun or the like, substantially as shown and described.
